UNITED STATES PATENT OFFICE.

WILLIAM W. NEWCOMB, OF BRADFORDSVILLE, KENTUCKY.

CAR-COUPLING.

SPECIFICATION forming part of Letters Patent No. 274,960, dated April 3, 1883.

Application filed February 5, 1883. (No model.)

To all whom it may concern:

Be it known that I, WILLIAM W. NEWCOMB, a citizen of the United States, residing at Bradfordsville, in the county of Marion and State of Kentucky, have invented certain new and useful Improvements in Link-Rests for Car-Couplers; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

My invention relates to car-couplers; and it consists in the construction, adaptation, and application to a coupler of a link-rest, by means of which the link is rigidly held in proper position for insertion in the mouth of the opposite coupler as the two cars come together, the jar occasioned by the meeting of the couplers serving to automatically release the rest mechanism, thereby allowing the link to operate loosely subsequent to the coupling of the cars, the adjustment of the link being accomplished without danger to the operator, as will be hereinafter more fully set forth.

In the drawings, Figure 1 is a front end view of a coupler, showing the link—which is in transverse section—as held by the rest mechanism in proper position for insertion in the mouth of an opposite coupler. Fig. 2 is a similar view of a coupler and link, showing the latter released from the rest mechanism. Fig. 3 is a side elevation of my improved device, also showing the link released from the rest mechanism, the draw-head of the coupler being shown in vertical longitudinal section. Fig. 4 is a side elevation of a portion of one and a longitudinal vertical section of a portion of another of two couplers, showing attached to the latter coupler a portion of my improved rest mechanism in the act of holding the link for insertion in the mouth of the opposite coupler, the couplers in this instance occupying planes of different height; and Fig. 5 is a transverse section of a coupler having applied thereto a modified form of rest mechanism.

To the under side of the draw-head of a coupler, A, is pivoted, as at a, a lever, B, which has a lateral extension, so as to be grasped and operated from the side of the car without

necessitating the operator to stand between the two cars while they are being coupled. To the lever is pivoted a stem, C, which passes vertically through a perforation, b, made through the bottom of the draw-head immediately behind the pin-opening c and at a proper distance therefrom. Upon the upper end of the stem C is constructed a depressing hook or angle, d, which, in conjunction with a rest shoulder or block, f, constructed upon the lower lip of the draw-head mouth, operates to hold the link in proper position for insertion in the mouth of the opposite coupler while the two cars are coming together, as shown in Figs. 1 and 4. Upon that side of the under portion of the draw-head which is opposite to the side occupied by the lever pivot or fulcrum a, as above described, is constructed a ratcheted keeper, E, by which the lever B is retained in position after having been depressed sufficiently to give to the outer end of the link—through the instrumentality of the hook d and fulcrum-rest f—the elevation or depression necessary to insure its entrance into the mouth of the opposite coupler. The spring F, actuating the slide-rest e, causes the normal position of the lever which rests upon it to be upward. The hold of the lever when engaged with any of the lower ratchets of the keeper E is sufficiently light to be broken by the jar consequent upon the jamming of the two couplers against each other as the two cars come together. The lever, being released from the keeper, is forced up by the spring, as shown in Figs. 2 and 3, carrying with it the hook d. Thus at the proper time—immediately subsequent to or at the same time of the coupling of the cars—the link is automatically relieved from the influence of the rest mechanism, and is allowed to operate loosely around the pins in the two couplers. The link g and pin h, used in connection with my improved device, are constructed in the usual well-known way.

I do not confine myself to the spring-replacing mechanism F and e, as the same effect may be produced by locating the lever above the coupler and replacing the lever pivot or fulcrum a between the stem C and keeper E, as shown in Fig. 5, the weight of the outer end of the lever acting as a substitute for the spring.

It will be observed that with my improved

rest mechanism the outer end of the link can be elevated or depressed to any desired degree and held in that position until automatically released by the coupling of the cars, as above described, the ratchets in the keeper E admitting of all necessary adjustments of the lever by which the depressing-hook is actuated and confined.

Having thus fully described my invention, what I claim as new, and desire to secure by Letters Patent, is—

1. In combination with a car-coupler provided with the usual pin and link, the laterally-projecting lever, the depressing-hook, rest-

shoulder or link-fulcrum, and keeper, substantially as described.

2. In combination with a car-coupler provided with the usual pin and link, the lever B, depressing-hook d, rest-shoulder or link-fulcrum f, keeper E, spring F, and slide-rest e, substantially as described.

In testimony whereof I affix my signature in presence of two witnesses.

WILLIAM W. NEWCOMB.

Witnesses:

JOHN M. ROBBINS,
JAS. A. BOWMAN.
